UNITED STATES PATENT OFFICE.

THEODORE S. SPEROS, OF CAMBRIDGE SPRINGS, PENNSYLVANIA.

SHOW CASE.

Application filed August 30, 1923. Serial No. 660,189.

This invention relates to improvements in show cases and more particularly to that type embodying a sliding top.

It is ordinarily desirable to support a display of merchandise upon the top of a show case, as, for example, a number of boxes of cigars, where the commodity to be dispensed is of this nature, but this cannot be conveniently done where the show case is provided with a sliding top or a top made up of slideable sections, although where such a top comprises, for example, two sections, a limited number of boxes of cigars may be supported upon the uppermost section of the top. However, as show case tops are ordinarily not built to sustain any considerable weight, and particularly where they are of the sliding type, it is usually found impracticable to so display the merchandise. In consideration of the foregoing, it is one of the important objects of the present invention to provide a show case embodying a slideable top so mounted and constructed that it may support a considerable display of merchandise and may be moved into and out of closed position without in any way disturbing or disarranging the display and without any likelihood of breakage of the top, notwithstanding the considerable weight which may be imposed thereon.

Another object of the invention is to provide a show case having a top mounted for sliding movement across the open upper side thereof in a front to rear direction so that, without disturbing the merchandise on display upon the said top, it may be slid rearwardly to open position thereby exposing to view the entire contents of the case and permitting the customer to make his selection, individually, from the merchandise contained therein. In this manner handling of the cigars or other merchandise by the salesman is entirely obviated, and provision is made for a more effectual display of the merchandise, and it is furthermore rendered more accessible.

In the accompanying drawings:

Figure 1 is a perspective view, parts being shown in section, of a show case constructed in accordance with the present invention;

Figure 2 is a top plan view of one end of the show case, the top being illustrated as partly open;

Fig. 3 is a detail transverse sectional view on the line 3-3 of Figure 2;

Fig. 4 is a front to rear sectional view on the line 4-4 of Fig. 2;

Fig. 5 is a view similar to Fig. 3 illustrating a modified form of the invention;

Fig. 6 is a detail sectional view on the line 6-6 of Fig. 5;

Fig. 7 is a perspective view of one of the rails of the structure shown in Figs. 5 and 6 removed from the case.

The show case embodying the invention comprises the usual body or case structure which is indicated in general by the numeral 1 and which in itself may be of any of the ordinary constructions except as regards its open top. The open top of the case comprises the usual front and rear rails indicated respectively by the numerals 2 and 3, and the side rails which are indicated by the numeral 4, and in order to accommodate certain elements of the structure embodying the invention, the side rails 4 are formed in their upper sides with longitudinally extending grooves indicated by the numeral 5. These grooves are of sufficient depth and breadth to accommodate a rod indicated by the numeral 6, the rod being preferably circular in cross section and being supported near its extremities in eye members 7 which are threaded or driven into the side rails 4 through the bottom wall of the grooves 5, the said eye members being open at their sides as indicated by the numeral 8 so that after they have been threaded or otherwise driven into place and the rod 6 has been mounted therein, they may be clinched upon the rod so as to hold the rod against longitudinal displacement.

The sliding top of the case is indicated by the numeral 9 and the same comprises a rectangular frame 10 including side rails 11 which overlie the side rails 4 of the top frame of the case 1, a pane of glass indicated by the numeral 12 being arranged within the frame 9 and constituting a supporting surface upon which any desired display of merchandise may be arranged. Eyelets 13 are threaded or otherwise driven into the underside of the side rails 11 of the frame 9, one of the eyelets being positioned near each forward corner of the slideable top 9. The eyelets 13 slidably engage the respective rods 6 and serve to guide the sliding top of the show case in its movement from open to closed position and vice versa. It will be evident that inasmuch as the eyelets 110

are located at the forward corners of the sliding top, the top may be slid to an extreme rear position without any likelihood of over-tilting and without disturbance of the display of merchandise thereon. It will be observed by reference to Fig. 3 of the drawings that the head of the eyelet 7 is square at its lower side so that when the shank of the eyelet is driven into the side rails 4 the said face of the head will rest squarely upon the flat bottom wall of the groove 5. In this manner the eyelets are rendered more substantial, and an accurate horizontal positioning of the rod 6 is effected.

In that form of the invention shown in Figs. 5, 6 and 7 of the drawings, the side rails of the case, which rails are indicated by the numeral 14, are formed each with a longitudinally extending groove indicated by the numeral 15, and seated within each groove 15 is a guide rail indicated in general by the numeral 16. This guide rail is preferably formed from an integral sheet metal blank provided at its ends with attaching ears 17 through which openings 18 are formed for the passage of securing elements 19 to secure the rails in position upon the rail 14 of the case. The said attaching ears 17 are preferably seated in countersinks formed in the upper side of the rail 14 at the ends of the groove 15 so that the upper side of the body of the rail 16 will be flush with the upper surface of the said rail 14 as clearly shown in Fig. 6 of the drawings. A slot 20 is formed longitudinally in the body of the rail 16, and the rail at its opposite longitudinal edges is provided with depending flanges 21 which seat against the inner faces of the side walls of the groove 15 and rest at their lower edges upon the bottom wall of the said groove. The formation of the flanges 21 serves to reinforce the body of the rail 16 and likewise the engagement of these flanges against the inner faces of the side walls of the groove, and the engagement of their lower edges against the bottom wall of the groove, serves to materially reinforce the connection of the rail with the rail 14.

The sliding top of the case in this form of the invention is indicated by the numeral 22 and the same is of the general structure

previously described and threaded into the under side of the side rails 23 of the said top, or otherwise secured to the under side of the top, is a headed guide comprising a shank 24 and a transverse head 25, the head extending at right angles with relation to the shank and the said shank engaging slidably through the slot 20 in the respective rail 16. By reference to Fig. 6 of the drawings it will be observed that the head 25 is received within the open underside of the rail 16 and rides in close proximity to the under side of the body or web portion of the rail. This form of the invention operates in substantially the same manner as the previously described form and presents all of the advantages possessed by the said previously described form.

Having thus described the invention, what is claimed as new is:—

In a show case, a body structure open at its top and having side and end walls with flat upper edge faces, a top slidably disposed upon the upper edge faces of the walls of said body structure and movable longitudinally of the end walls from a position overlying and closing the open top of the show case to a position substantially wholly displaced beyond the open top, said end walls having longitudinally extending grooves opening through their upper edge faces and having recesses leading from the ends of the grooves and constituting seats, rails mounted in said grooves and each having an upper wall formed with a longitudinally extending slot and depending side walls in close contacting engagement with the side walls of the groove with their lower edges resting upon the bottom of the groove, said upper wall being extended beyond the faces of the depending side walls and secured in said seats, and headed elements extending downwardly from opposite ends of the sliding top with their shank portions passing through the slots in the respective rails and having heads slidably engaging beneath the upper walls of the rails and preventing movement of said elements out of engagement with the rails.

In testimony whereof I affix my signature.

THEODORE S. SPEROS. [L.S.]
